UNITED STATES PATENT OFFICE

WALTER H. COOK, OF NEW ORLEANS, LOUISIANA.

SHOCK-ABSORBER.

1,073,401.

Specification of Letters Patent. Patented Sept. 16, 1913.

Application filed March 8, 1913. Serial No. 752,438.

To all whom it may concern:

Be it known that I, WALTER H. COOK, a citizen of the United States, residing at New Orleans, in the parish of Orleans and State of Louisiana, have invented new and useful Improvements in Shock-Absorbers, of which the following is a specification.

This invention relates to improvements in shock absorbers and it proposes a construction of that general type wherein the impulses of the main spring are taken up by a cushioning element through the intermediary of a shock transmitting element which acts characteristically with wave-like compressing effect on the cushioning element. An illustration of the type of construction thus identified is to be found in my U. S. Letters Patent No. 1,058,411, granted April 8, 1913, and the present improvement involves a specific organization for carrying out the principles of operation explained in said Letters Patent.

The object of the invention is to provide an organized structure which secures all the advantages incident to the type to which it belongs, and is of such nature as to have special adaptability, in respect of compactness, sensitiveness, and efficiency of action, to particular makes of cars.

The adaptability of the construction to particular makes of cars depends upon its capacity for the arrangement of the cushioning element below the axle, in combination with a main spring above the axle, and for the efficient transmission of the impulses of the main spring to the shock transmitting element in such manner that a direct transmission of the impulses of the main spring in which there is little, if any, lost motion, is achieved without any substantial interference with the freedom of movement of said spring.

Embodiments of the invention are illustrated in the accompanying drawings, wherein:

Figure 1 is a view in elevation, illustrating a shock absorber in which the features of the invention are incorporated in its application to the front axle of a car; Fig. 2 is a similar view illustrating an alternative construction; Figs. 3 and 4 are similar views illustrating the mechanical elements shown in Figs. 1 and 2 respectively in their application to a shock absorbing organization especially adapted for the rear axle; and Fig. 5 is an elevation illustrating an alter-

native form of connection between the main spring and the shock transmitting element, and which is applicable to either a front axle or a rear axle shock transmitting organization of the general nature illustrated in Figs. 1 and 3.

Similar characters of reference designate corresponding parts throughout the several views.

In the construction shown in Fig. 1, the main spring is shown at 1, and is arranged above the axle 2, and the cushioning element is shown at 3, and is arranged below said axle. The impulses of the main spring are transmitted to the cushioning element by a shock transmitting element 4. The cushioning element 3 is in the nature of an elongated air tube which is of approximately the same length as the width of the machine; and the shock transmitting element 4 is in the nature of a spring bar which is parallel to and of approximately the same length as the cushion 3 and is connected centrally of its length to the axle 2, as by a pivot 5, for movement in a vertical plane. The opposed bearings for the cushion 3 are provided by the bar 4, and the axle 2, the latter for this purpose carrying a depending frame 6 upon which the cushion 3 rests, and the bar 4 engaging the upper side of said cushion.

The pulsations of the main spring are transmitted to the bar 4 by connections which allow the requisite freedom of movement of said spring, and yet transmit its pulsations with a minimum degree of loose play or lost energy. The connections are, of course, duplicated at each end of the axle, and, as illustrated in Fig. 1, comprise a radius link 7 which is pivoted to a lug 8 secured on the axle, a link 9 which connects the radius link 7 and the adjacent end of the spring 1, and a link 10 which connects the radius link 7 and the adjacent end of the bar 4, the links 9 and 10 being preferably coaxially pivoted to the link 7. It will be apparent that the spring 1 has the requisite freedom of movement or play, and that the link 10 moves under the impulses of said spring in substantially straight lines, perpendicular to the axis of the cushion 3. Inasmuch as the links 10 are connected to the ends of the bar 4, the bar 4 will produce a wave-like compression of the cushion 3, from the ends toward the center thereof, as is obvious. The construction shown in Fig. 2 differs from the construction shown in Fig.

in the nature of the connections between the main spring and the shock transmitting element, and also in that the frame 6, shown in Fig. 1, is not employed, but instead, the 5 cushioning element 3 is arranged directly against the under face of the axle 2, and the shock transmitting bar which, in this instance, is designated 4^a, engages the under-side of the cushion 3. The bar 4^a, like the 10 bar 4, is connected, as by a pivot 5, to the axle 2. The connections between the spring 1 and the bar 4^a comprise levers 11 pivoted centrally thereof to lugs 12 mounted on the axle 2, pivot pin connections between the inner 15 ends of the levers 11 and the adjacent end of the spring 1, and link connections 13 between the outer ends of the levers 11 and the adjacent ends of the bar 4^a. Whereas in the organization shown in Fig. 1 a relative 20 downward movement of the ends of the spring 1 will produce corresponding downward thrusts of the links 10, in the organization shown in Fig. 2, a relative downward movement of the ends of the spring 1 produces 25 an upward thrust of the links 13. It is for this reason that the shock transmitting element is arranged above the cushion in the construction of Fig. 1, and below the cushion in the construction of Fig. 2.

Figs. 3 and 4 illustrate organizations similar to those of Figs. 1 and 2 respectively, but in connection with a rear axle having a centrally arranged gear case A. Whereas in the constructions of Figs. 1 and 2, a single 30 air cushion extending practically for the width of the machine is employed, in the construction shown in Figs. 3 and 4, two air cushions, as 3^a, are employed, the cushions 3^a being arranged at opposite sides of the 35 gear case A. In the construction shown in Fig. 3, a depending yoke 14 is fitted upon the rear axle 2^a at each side of the gear case A. This yoke furnishes support for a frame- 40 6^a corresponding to the frame 6 of Fig. 1, and for a shock transmitting bar 4^b which is pivoted at its inner end, as at 5^b, between the arms of the yoke 14. The connections for transmitting the impulses of the spring 1^a to the two bars 4^b are the same as those 45 employed in Fig. 1 for transmitting the impulses of the spring 1 to the bar 4, and are designated by the same reference characters. The construction shown in Fig. 4 involves the use of the cushions 3^a at each side of the 50 gear case A, as in Fig. 3. The shock transmitting bars are indicated by the character 4^c, one of said bars being employed for each cushion 3^a and being arranged relatively thereto in the same manner as the bar 4^a is 55 arranged relatively to the cushion 3 in Fig. 2. The connections between the ends of the spring 1^a and the shock transmitting bars 4^c are similar to the connections between the ends of the spring 1 and the bar 4^a in Fig. 60 2, and are designated by the same reference

characters. The bars 4^c are pivoted at their inner ends to yokes 14^a, generally similar in construction and arrangement to the yokes 14 of Fig. 3. Inasmuch as the rear axle 2^a is generally of cylindrical outline, it is not practical to arrange the cushions 3^a directly against said rear axle, but bearing plates 15 are provided which are rigid with the axle 2^a and engage the upper sides of the cushions 3^a, the support for the plates 15 including the yokes 14^a and brackets 16 secured adjacent the outer ends of the axle 2^a. 70 75 75

Fig. 5 shows mechanical connections between the main spring and the shock transmitting element which may be employed in lieu of the elements 7, 8, 9, and 10, shown in Figs. 1 and 3. In this latter instance, the ends of the spring 1 are connected to radius links 7^a which, at their outer ends, are pivoted to lugs 8^a secured on the axle, and having a suitable upward and inward inclination. The pivotal connections of the links 7^a and the spring 1 form also the pivots of links 10^a which, at their other ends, are connected to the adjacent ends of the bar 4, and are of slight ogee curvature. The principal difference between the construction shown in Fig. 5 and the construction shown in Fig. 1 is the omission from the former of the link 9. But in omitting the link 9, the lugs 8^a and the links 10^a are so arranged that the compressive thrusts of said links 10^a are substantially perpendicular to the axis of the cushion 3. 80 85 90 95

Having fully described my invention, I claim:

1. In a shock absorber, the combination with a vehicle axle, of a main spring arranged above the axle, pneumatic tube cushioning means arranged below the axle, 105 shock transmitting bar means engaging the cushioning means, an element pivotally mounted at each end of the axle and pivotally connected to the adjacent end of the main spring, and a link pivoted to said element at one side of the fixed pivot of the latter and also pivoted to the adjacent end of said shock transmitting bar means.

2. In a shock absorber, the combination with a vehicle axle, of a main spring arranged above the axle, pneumatic tube cushioning means arranged below the axle, shock transmitting bar means engaging the cushioning means, a radius link pivotally mounted at each end of the axle, a link connecting the radius link and the adjacent end of the main spring, and a second link connecting the radius link and the adjacent end of the shock transmitting bar means. 115 120

3. In a shock absorber, the combination with a vehicle axle, of a main spring arranged above the axle, pneumatic tube cushioning means arranged below the axle, shock transmitting bar means having a fixed point of support and engaging the cushioning 125 130

- means, an element pivotally mounted at each end of the axle and pivotally connected to the adjacent end of the main spring, and a link pivoted to said element at one side of the fixed pivot of the latter and also pivoted to the adjacent end of said shock transmitting bar means.
4. In a shock absorber, the combination with a vehicle axle, of a main spring arranged above the axle, pneumatic tube cushioning means arranged below the axle, shock transmitting bar means having a fixed point of support and engaging the cushioning means, a radius link pivotally mounted at each end of the axle, a link connecting the radius link and the adjacent end of the main spring, and a second link connecting the radius link and the adjacent end of the shock transmitting bar means.
5. In a shock absorber, the combination with a vehicle axle, of a main spring arranged above the axle, a cushioning tube arranged below the axle, a shock transmitting bar, engaging the tube and connected at a central point with the axle, an element pivotally mounted at each end of the axle and pivotally connected to the adjacent end of the main spring, and a link pivoted to said element at one side of the fixed pivot of the latter and also pivoted to the adjacent end of said shock transmitting bar.
6. In a shock absorber, the combination with a vehicle axle, of a main spring arranged above the axle, a cushioning tube arranged below the axle, a shock transmitting bar engaging the tube and connected at a central point with the axle, a radius link pivotally mounted at each end of the axle, a link connecting the radius link and the adjacent end of the main spring, and a second link connecting the radius link and the adjacent end of the shock transmitting bar means.
7. In a shock absorber, the combination with an axle, of a main spring arranged above the axle, cushioning means arranged below the main spring and having support from the axle, shock transmitting bar means engaging the cushioning means, an element pivotally mounted at each end of the axle and pivotally connected to the adjacent end of the main spring, and a link pivoted to said element at one side of the fixed pivot of the latter and also pivoted to the adjacent end of said shock transmitting bar.
8. In a shock absorber, the combination with an axle, of a main spring arranged above the axle, pneumatic tube cushioning means arranged below the main spring and having support from the axle, shock transmitting bar means engaging the cushioning means, an element pivotally mounted at each end of the axle and pivotally connected to the adjacent end of the main spring, and a link pivoted to said element at one side of the fixed pivot of the latter and also pivoted to the adjacent end of said shock transmitting bar.

In testimony whereof I have hereunto set my hand in presence of two subscribing witnesses.

WALTER H. COOK.
